SOLDERING IRON STAND

Hardin S. Wedmore, Santa Cruz, Calif.

Application March 10, 1947, Serial No. 733,506

11 Claims. (Cl. 113—111)

1

This invention relates to a soldering iron stand and has for one of its objects the provision of a stand adapted to support a soldering iron during intervals between use, and which stand includes means for preventing scaling and oxidation of the tip.

Another object of the invention is the provision of a stand for electric soldering irons that includes means for controlling the temperature of such irons and for preventing scaling of the tip.

It is well known in industries where soldering irons are used that the tips will scale and oxidation will occur if a soldering iron is allowed to remain with the current turned on for substantial periods between use. Continuous overheating causes oxidation and tends to shorten the life of the soldering iron.

The most common method employed in an attempt to overcome the above objectionable occurrences has been to place the iron in a holder that dissipates the heat to a degree that tends to prevent overheating of the tip. Other methods include thermostatically controlled devices associated with the stands for regulating the temperature of the irons placed on the stands. However, insofar as I am aware said stands and devices do not prevent scaling, although they may tend to retard it.

With the present invention the temperature of the iron placed on the stand is maintained at the desired point and the tendency of the iron to scale is substantially eliminated.

Other objects and advantages will appear in the drawing and description.

In the drawings,

Fig. 1 is a side elevational view of the stand; partly in section.

Fig. 2 is a sectional view taken along line 2—2 of Fig. 1.

Fig. 3 is a sectional view taken along line 3—3 of Fig. 2.

In detail, the stand illustrated comprises an elongated container 1 that is adapted to lie horizontally on one of its sides when in use, the said container having a flat side 2 (Fig. 3) adapted to support the container in a stable position on a horizontal surface.

At one end of said container is a filling opening that is closed by a quick detachable conventional closure cap 3 (Fig. 1) while the other end 6 is flat and adapted to support the container on end on a horizontal surface when the same is not in use. Thus the cap will be uppermost when the container is not in use.

Secured to the upper side of the container 1 is an upwardly opening, elongated channel 4 having perforated sides, said channel extending longitudinally of the container 1 and centrally of its upper side. This channel 4 terminates at one end in a cylindrical extension 5 that projects to

2

one side of the container. The sides of said extension are imperforate and it is of a length to fully enclose the tip of a soldering iron. (Fig. 1) when the shell 7 that encloses the heating element of a conventional electric soldering iron is in channel 4 adjacent the extension 5, and when the tubular shank 8 that connects between handle 9 and said shell 7 extends in channel member 4 across the top of container 1.

The sides of channel member 4 are preferably of progressively decreasing height in a direction extending away from extension 5, and the end of the channel member 4 opposite extension 5 may almost come to a point at the bottom side of the channel adjacent end 4.

As above mentioned, the channel member 4 is preferably perforated, and in the portion of the sides of the channel that are adjacent extension 5, pairs of said perforations 10 may be in axial alignment in opposite sides of the channel member for receiving the oppositely outwardly directed ends 11 of a generally U-shaped elongated wire, the legs of which are designated 12 (Fig. 2) and the closed end being designated 13.

The legs 12 preferably extend toward each other adjacent the ends 11 as indicated at 14 for supporting the shell 6 of the iron, and the ends 11 are positioned in the pair of aligned openings 10 that will position closed end 13 of the wire so that it will engage handle 9 when the tip 6 is in proper position enclosed within extension 5. Thus, end 11 may function to provide a stop and position indicator for the iron, and as the wire support may be so moved as to position end 11 at different distances from extension 5, it will be seen that means is provided to accommodate the stand to different irons. The closed end 13 of the U-shaped wire is adapted to engage the shank 8 of the wire adjacent handle 9 to resist any tendency of the iron to tilt when in the position seen in Fig. 1, although a certain amount of tilt would not materially change the result accomplished.

A conduit 15 extends from a point adjacent the bottom 2 and cap 3 of the container to a point within extension 5, and a portion 16 of the conduit that is in extension 5 may extend above the bottom of the latter and have its upper side removed so that any liquid flowing into the portion 16 will be exposed. The outer end of portion 16 is preferably closed.

While a heat resistant wick may be positioned in the portion 16, it is preferably left open.

Within extension 5 is an open ended tube 17 of screen material that forms a liner for said extension with portion 16 of conduit 15 within said tube and close to the lower side of the latter. The tube 17 is preferably of two thicknesses and with a layer of relatively porous material between them. This layer may be of any suitable non-

flammable material such as asbestos, spun glass, etc.

Within container 1 may be any suitable heat vaporizable antiscalming liquid, such as distilled water and bismuth-carbonate preferably in the ratio of about $\frac{1}{2}$ pint of water to $\frac{1}{2}$ teaspoonful of the bismuth-carbonate. Or valve oil and alcohol may be used or any other suitable antiscalming liquid of which there are a number.

In actual practice, the wire in channel member 4 prevents the tip of the iron from contacting anything within extension 5, and heat from the iron will heat the conduit 15 that extends into the container causing sufficient evaporation of the liquid within the container to force liquid into portion 16 where it is vaporized, some overflowing for absorption by the porous material of the liner.

The vapors within extensions 5 surround the tip and are in engagement therewith, thus preventing oxidation and sealing of the tip. A transfer of heat to the vapors also occurs tending to prevent overheating of the tip.

Usually the operator merely tips the container, upon first using the stand so that some liquid will flow into portion 16 to wet the asbestos or other similar material held by the screen. Thereafter sufficient moisture will automatically be supplied to produce the desired vapors.

The screen liner in extension 5 functions to tend to retain the vapors in the extension from escaping through the open ends, and it is very effective in performing this function.

When the stand is not in use, the operator may merely stand it on end for convenience, although it may be allowed to lie flat if desired.

It is to be understood that the detailed description and drawings are not intended to be restrictive of the invention, but are merely illustrative of a preferred form thereof.

I claim:

1. In combination with a container adapted to contain a supply of heat vaporizable anti-scaling liquid, means for supporting a hot soldering iron adjacent said container for vaporizing said liquid in the said container and for creating a slight vapor pressure in said container, means for conducting liquid under said pressure to a point adjacent the tip of said iron for vaporizing said liquid at said point, a shield around said tip when supported on said first mentioned means for causing the vapors generated at said point to surround said tip in engagement therewith.

2. In combination with a container adapted to contain a supply of heat vaporizable anti-scaling liquid, means for supporting a hot soldering iron adjacent said container for vaporizing said liquid in the said container and for creating a slight vapor pressure in said container, means for conducting liquid under said pressure to a point adjacent the tip of said iron for vaporizing said liquid at said point, a shield around said tip when supported on said first mentioned means for causing the vapors generated at said point to surround said tip in engagement therewith, said first mentioned means being adapted to support said iron with said tip in spaced relation to said shield.

3. A soldering iron stand comprising a container for a heat vaporizable anti-scaling liquid, a member on said container for supporting said iron in a generally horizontally extending position with its tip offset to one side of said con-

tainer but adjacent thereto, means for conducting liquid from said container to a point adjacent and below said tip for vaporization of said liquid at said point whereby said vapors will engage said tip upon rising.

4. A soldering iron stand comprising a container for a heat vaporizable anti-scaling liquid, a member on said container for supporting said iron in a generally horizontally extending position with its tip offset to one side of said container but adjacent thereto, means for conducting liquid from said container to a point adjacent and below said tip for vaporization of said liquid at said point whereby said vapors will engage said tip upon rising, means for retaining said vapors around said tip.

5. A soldering iron stand comprising a container for a heat vaporizable anti-scaling liquid, a member on said container for supporting said iron in a generally horizontally extending position with its tip offset to one side of said container but adjacent thereto, means for conducting liquid from said container to a point adjacent and below said tip for vaporization of said liquid at said point whereby said vapors will engage said tip upon rising, means for retaining said vapors around said tip including a cylindrical body of non-inflammable relatively porous material.

6. A soldering iron stand comprising a container for a heat vaporizable anti-scaling liquid, a member on said container for supporting said iron in a generally horizontally extending position with its tip offset to one side of said container but adjacent thereto, means for conducting liquid from said container to a point adjacent and below said tip for vaporization of said liquid at said point whereby said vapors will engage said tip upon rising, an open-ended tube of perforated sheet material in which said tip is adapted to be inserted when on said member, said conduit opening at its discharge end into said tube.

7. A soldering iron stand comprising a container for a heat vaporizable anti-scaling liquid, a member on said container for supporting said iron in a generally horizontally extending position with its tip offset to one side of said container but adjacent thereto, means for conducting liquid from said container to a point adjacent and below said tip for vaporization of said liquid at said point whereby said vapors will engage said tip upon rising, an open-ended tube of perforated sheet material in which said tip is adapted to be inserted when on said member, said conduit opening at its discharge end into said tube, and a tubular liner of screen material within said tube.

8. A soldering iron stand comprising a container for a heat vaporizable anti-scaling liquid, a tubular open-ended shield secured to said container and projecting laterally from said container, said shield being adapted to receive the tip of said iron therein when the latter is in a position extends across the top of said container, means for supporting said iron on said container in said position, means for conducting liquid from the said container into said shield for vaporizing by the heat from said tip.

9. A soldering iron stand comprising a container for a heat vaporizable anti-scaling liquid, a tubular open-ended shield secured to said container and projecting laterally from said container, said shield being adapted to receive the tip of said iron therein when the latter is in a position

extends across the top of said container, means for supporting said iron on said container in said position, means for conducting liquid from the said container into said shield for vaporizing by the heat from said tip, means connected with said shield for supporting said tip spaced within said shield.

10. A soldering iron stand comprising a container for a heat vaporizable anti-scaling liquid, a tubular open-ended shield secured to said container and projecting laterally from said container, said shield being adapted to receive the tip of said iron therein when the latter is in a position extends across the top of said container, means for supporting said iron on said container in said position, means for conducting liquid from the said container into said shield for vaporizing by the heat from said tip, means connected with said shield for supporting said tip spaced within said shield, and a relatively porous liner within said shield for tending to retain said vapors within said shield and around said tip.

15. 11. A soldering iron stand comprising a container for a heat vaporizable anti-scaling liquid, a tubular open-ended shield secured to said container and projecting laterally from said container, said shield being adapted to receive the

tip of said iron therein when the latter is in a position extends across the top of said container, means for supporting said iron on said container in said position, means for conducting liquid from said container into said shield for vaporizing by the heat from said tip, and a tubular screen within said shield for extending around said tip when the arm is in said position.
